PUMPING MECHANISM

Chalon E. Bridwell, Detroit, Mich.

Application January 2, 1940, Serial No. 311,994

13 Claims. (Cl. 103—180)

My invention relates to a new and useful improvement in a pumping mechanism adapted primarily for use in pumping from deep wells such as oil wells or the like. In this type of pump I use a reciprocating barrel operating over a stationary plunger anchored at the bottom end. In the reciprocating barrel I have provided a loose slideable valve of a sleeve-like nature adapted for moving to closed position on the lifting stroke. In the barrel I also provide an axially movable valve carried by a stationary part and movable axially relative thereto within predetermined limits.

It is an object of the present invention to provide in this last-named valve a construction whereby the engagement of the valve with the end of the plunger will form a seal, the end of the plunger serving as a valve seat.

Another object of the invention is the provision of a construction whereby the valve, in addition to being axially movable, may also slightly rotate so that when reseating on the seat it does not engage in the same relative position.

Another object of the invention is the provision in a pumping mechanism of this class of a valve axially movable within predetermined limits provided with a guide engageable with the inner surface of the reciprocating barrel so that the valve is maintained centered at all times and the engagement of the guide portion of the valve with the inner surface of the reciprocating barrel is not required to act as a sealing valve.

Another object of the invention is to provision in a pumping mechanism of this type of a loosely mounted valve in the lower end of the stationary plunger.

Another object of the invention is the provision in a pumping mechanism of a structure whereby the valve cage may be eliminated and whereby an increased fluid passage throughout the entire pump may be obtained thus increasing the volume output of the pump.

Other objects will appear hereinafter.

It is recognized that various changes and modifications may be made in the details of structure of this invention without departing from the spirit of this invention, and it is intended that such variations and modifications may be brought within the scope of the claims appended hereto.

Forming a part of the description are drawings, in which,

of the part of the invention forming a continuance of the part shown in Fig. 1 with intermediate parts broken away,

Fig. 3 is a longitudinal sectional view of the invention with parts broken away and forming a continuance of the part shown in Fig. 2 with intermediate parts removed.

Fig. 4 is a fragmentary, central, longitudinal sectional view of the invention forming a continuation of the part shown in Fig. 3 with an intermediate portion removed.

Fig. 5 is a sectional view taken on line 5—5 of Fig. 3.

Fig. 6 is a sectional view taken on line 6—6 of Fig. 3.

Fig. 7 is a fragmentary central longitudinal sectional view of a modified form of the invention,

Fig. 8 is a sectional view taken on line 8—8 of Fig. 7.

Fig. 9 is a sectional view taken on line 9—9 of Fig. 7.

In the drawings, I have illustrated the invention used with an oil well in which there is provided a tube 9 extending from the bottom of the well to the top thereof, and serving as the conduit for conveying the pump liquid from the bottom of the well to the top. This tube, of course, is stationary. Extending downwardly from the top of the well interiorly of the tubing is a sucker rod which is adapted to be attached by a suitable connection to the threaded end 10 of the guide rod which is provided with a hexagonal portion 11 against which the lock nut 13 is threaded. This hexagonal portion projects through the scored end 12 of a top adapter 14 which is of sleeve-like construction and threaded at its lower end to the upper end of the upper barrel tube 15. Below the hexagonal portion 11 of the guide rod is an enlargement 16 which engages the inner surface of the adapter 14 and which on the upper stroke contacts the shoulder 17 formed on the adapter so that on the upper stroke after the enlargement 16 engages the

45 shoulder 17, the adapter will travel upwardly in unison with the sucker rod. The adapter is provided with openings 18 through which liquid may flow into the interior of the tubing 9. The lower end of the guide rod is threaded as at 19 into a sleeve 20, into which also is threaded the threaded upper end 21 of the rod 22 which projects upwardly from the valve seat forming head 23. The sleeve 20 forms a part of the tube 24, which may be termed a stop tube, for engaging the 55 loosely positioned sleeve valve 25'. Openings 26

are formed in the stop tube 24. Projecting downwardly from the valve head 23 is a tubular body having openings 25 formed therein and provided with the enlarged terminal guide portion 26 which engages against the inner face 27 of the upper barrel 15 in a slide fit. This upper barrel 15 is threaded to one end of a coupling 28 which has a bore 29 formed therethrough. The lower end of this coupling 28 is threaded to the upper end of the lower barrel tube 30. The lower end of this barrel tube 30 is threaded onto the upper end of a sleeve 31 which may be termed a barrel tube pull nut. Slidable in the barrel section is a guide section 32 which is formed in the nature of a tube and adapted to engage against the inner surface 33 of the barrel section 30 by a slide fit but not by such a close fit as to form a liquid seal. A reduced portion 34 extends outwardly from the lower end of the member 32 and is provided with lateral openings 35. This reduced portion terminates in a head 36, the face 37 of which serves as a valve when engaging against the end face 38 of the plunger 39. This plunger is stationary, as will appear from the description which follows. Projecting outwardly from the head 36 centrally thereof is a rod 40, the lower end of which is provided with an axially extending elongated slot 41 through which extends a pin 42 which is carried by and extends diametrically of the plunger 39. The slot 41 is of greater width than the outside diameter of the pin 42 so that a rotation of the guide section 32 of the valve head 36 within predetermined limits may take place.

The lower end of the plunger is threaded onto the upper end of a pull tube fitting 43. Threaded into the lower end of this fitting 43 is a pull tube 44 which threads at its lower end into the threaded bore of a pull tube nut 45. Threaded onto the end of this pull tube nut 45 is a valve cage 46, the lower end of which threads onto an anchor shoe adapter 47 which is provided with the tapered end 48 engaging in the tapered seat 49 of the anchor shoe 50. This anchor shoe 50 is connected by the anchor shoe coupling 51 to the tubing 9. Threaded into the lower end of the anchor shoe is a strainer tube 52 having openings 53 formed therein. Carried by the lower end of the anchor shoe adapter 47 is the gas separator tube 54.

Projecting downwardly from the pull tube nut 45 centrally thereof is a valve guide rod 55 which has a socket 56 formed in its lower end for reception of a stem 57 projecting upwardly from the valve head 58. This valve head 58 is adapted to engage the face 59 of the valve sleeve 60 which is held in position on the upper end of the anchor shoe adapter 47, by means of the valve cage 46.

The inner face of the upper end of the top adapter 14 in which the hexagonal portion 11 of the guide rod engages is formed flat-faced so that the guide rod 11 cannot rotate relatively to the top adapter 14. Consequently when it is desired to guide the sucker rod string onto the threaded portion 10 and the sucker rod string is rotated, the guide rod will not be able to rotate because in the lower end of the barrel tube nut 31 there are formed notches 65 in which engage the lugs 66 extending upwardly from the pull tube nut 45. This nut 45 being stationary and the lugs 66 engaging in the notches 65 will prevent any rotation of the barrel tubes and connected parts.

In operation, when the guide rod is pulled upwardly enlargement 16 will engage the shoulder

17 as shown in the drawings, and further continued upward movement will move the parts 14, 15, 30, and 31 upwardly, and in such upward movement the member 23 will engage the end of the sleeve valve 25 so that a leak-proof connection is effected between these parts. Continued upward movement then will effect a suction in the movable barrel sections below the valve head 23. This will cause the valve head 58 to move off its seat as shown in the drawings. Simultaneously, the valve face 37 will move out of engagement with the valve face 38 and liquid will pass upwardly through the tube 54 into the interior of the cage 46 through the pull tube 44 and through the plunger 39 outwardly through the bore 38' around the head 36 and into the interior of the member 32 through the openings 35.

On the down stroke the valve head 58 will move onto its seat by gravity or by the force of the liquid above. The valve face 37 will engage the valve face 38 and the valve 25 will move off its seat to allow the liquid to pass above. It will be noted that the engagement of the valve faces 37 and 38 effects a leak-proof seal through the engagement of but a pair of cooperating parts, one of these parts being the upper end of the plunger. It will also be noted that a slight relative rotation of these faces may take place to assure a tight sealing. Experience has shown that this type of a seal is most efficient and is subjected to a minimum amount of wear, eliminating the necessity of "pulling" the pump for valve changes. It will thus be seen that I have provided a stationary plunger with reciprocating barrel tubes and have utilized a minimum number of parts to provide a seal productive of the results mentioned. It will be noted that one of the sealing parts of the valve is movable while the other is stationary relatively to the stationary plunger. This type of valve control is most efficient where a quantity of sand is being pumped with the liquid.

In the structure shown in Fig. 1, the valve head 36 is permitted but a slight rotation. The structure shown in Fig. 4 differs in this regard from the structure illustrated in Fig. 1. In Fig. 1 the pin 42 limits the axial movement of the head 36 relatively to the plunger 39. In the form shown in Fig. 4, the plunger 39' is provided with an extension 67 which is threaded thereon to provide an internal shoulder 68 on the plunger 39'. A guide sleeve 32' is provided with the reduced portion 34' having the openings 35' formed therein, this reduced portion terminating in the elongated head 36', the end face 37' of which forms a valve facing to engage the end face 38' of the extension 67. Formed in the end of the head 36' is a socket 68' in which is inserted one end 69 of a stem 40' which may be secured to the head 36' in any suitable manner but which is illustrated secured thereto by means of the pin 70. Formed on the end of the rod 40' is a head 71 which is of larger outside diameter than the inside diameter of the extension 67 so that this head may engage against the shoulder 68 and thus limit axial movement of the valve mechanism while the valve mechanism is permitted to freely rotate an entire revolution. The same advantages recited concerning the structure of Fig. 1 are also present in the structure shown in Fig. 4.

What I claim is:

1. In a pumping mechanism of the class described, a stationary tubular plunger; a reciprocating tube embracing said plunger; means for reciprocating said tube, one end of said plunger

providing a valve seat; a valve head in said tube having a valve seat engageable with the valve seat on said plunger end; a tubular guide member extending from said valve head and engaging in said reciprocating tube in a slide fit, there being lateral openings formed in said tubular guide member intermediate its ends.

2. In a pumping mechanism of the class described, a stationary tubular plunger; a reciprocating tube embracing said plunger; means for reciprocating said tube, one end of said plunger providing a valve seat; a valve head in said tube having a valve seat engageable with the valve seat on said plunger end; a tubular guide member extending from said valve head and engaging in said reciprocating tube in a slide fit, there being lateral openings formed in said tubular guide member intermediate its ends; and means for limiting the rotation of said valve head beyond a predetermined degree.

3. In a pumping mechanism of the class described, a stationary tubular plunger; a reciprocating tube embracing said plunger; means for reciprocating said tube, one end of said plunger providing a valve seat; a valve head in said tube having a valve seat engageable with the valve seat on said plunger end; a tubular guide member extending from said valve head and engaging in said reciprocating tube in a slide fit, there being lateral openings formed in said tubular guide member intermediate its ends; means for limiting the rotation of said valve head beyond a predetermined degree, said valve head being axially movable relative to said plunger, and means for limiting the axial movement of said valve head relatively to said plunger in one direction beyond a predetermined distance.

4. In a pumping mechanism of the class described, a stationary tubular plunger; a tubular member embracing said plunger and reciprocable relative thereto axially thereof, said plunger being tubular; a tubular sleeve positioned in said tubular member and engaging therein in a slide fit and movable axially relative thereto; a head on one end of said tubular sleeve for closing said end, the outer face of said head providing a valve and adapted to engage against the end of said plunger and close the passage therethrough, said tubular sleeve having lateral openings formed therein between its open end and its closed end.

5. In a pumping mechanism of the class described, a stationary tubular plunger; a tubular member embracing said plunger and reciprocable relative thereto axially thereof, said plunger being tubular; a tubular sleeve positioned in said tubular member and engaging therein in a slide fit and movable axially relative thereto; a head on one end of said tubular sleeve for closing said end, the outer face of said head providing a valve and adapted to engage against the end of said plunger and close the passage therethrough, said tubular sleeve having lateral openings formed therein between its open end and its closed end; a rod extending from the outer face of said head and provided with an elongated slot; and means carried by said plunger and engaging in said slot for limiting rotating and axial movement of said head beyond a predetermined degree.

6. In a pumping mechanism of the class described, a stationary tubular plunger; a reciprocating tubular member embracing said plunger and movable longitudinally thereof; a tubular guide sleeve positioned in said tubular member in a slide fit and movable axially thereof; a head closing one end of said sleeve, said sleeve having

lateral openings formed therein intermediate said head and the open end of said sleeve, said plunger having a central passage formed therethrough, said head being engageable with the end of said plunger for closing one end of said passage; means extending from said head into said plunger; and means on said plunger engageable with said extending means for limiting axial movement of said sleeve relatively to said plunger beyond a predetermined distance.

7. In a pumping mechanism of the class described, a stationary tubular plunger; a reciprocating tubular member embracing said plunger and movable longitudinally thereof; a tubular guide sleeve positioned in said tubular member in a slide fit and movable axially thereof; a head closing one end of said sleeve, said sleeve having lateral openings formed therein intermediate said head and the open end of said sleeve, said plunger having a central passage formed therethrough, said head being engageable with the end of said plunger for closing one end of said passage; means extending from said head into said plunger; and means on said plunger engageable with said extending means for limiting axial movement of said sleeve relatively to said plunger beyond a predetermined distance and for limiting rotative movement of said sleeve relatively to said plunger beyond a predetermined degree.

8. In a pumping mechanism of the class described, a stationary vertically directed plunger having a central passage formed therein, the face of the upper end of said plunger providing a valve seat; a reciprocating tubular member embracing said plunger in snug relation and slidably axially thereof; a tubular guide sleeve in said tubular member and engaging the same in a slide fit and movable axially thereof; a head for closing one end of said guide sleeve, said guide sleeve having openings formed therein intermediate its open end and its closed end, the outer face of said head being engageable with said valve seat for closing the passage through said plunger.

9. In a pumping mechanism of the class described, a stationary vertically directed plunger having a central passage formed therein, the face of the upper end of said plunger providing a valve seat; a reciprocating tubular member embracing said plunger in snug relation and slidably axially thereof; a tubular guide sleeve in said tubular member and engaging the same in a slide fit and movable axially thereof; a head for closing one end of said guide sleeve, said guide sleeve having openings formed therein intermediate its open end and its closed end, the outer face of said head being engageable with said valve seat for closing the passage through said plunger, and an abutment member carried by said head and extending into said plunger; and means on said plunger engageable with said abutment member for limiting axial movement of said head beyond a predetermined distance.

10. In a pumping mechanism of the class described, a stationary vertically directed plunger having a central passage formed therein, the face of the upper end of said plunger providing a valve seat; a reciprocating tubular member embracing said plunger in snug relation and slidably axially thereof; a tubular guide sleeve in said tubular member and engaging the same in a slide fit and movable axially thereof; a head for closing one end of said guide sleeve, said guide sleeve having openings formed therein intermediate its open end and its closed end, the

outer face of said head being engageable with said valve seat for closing the passage through said plunger, and an abutment member carried by said head and extending into said plunger; means on said plunger engageable with said abutment member for limiting axial movement of said head beyond a predetermined distance; and means for limiting rotation of said sleeve beyond a predetermined degree.

11. In a pumping mechanism of the class described, a stationary tubular plunger mounted in vertical position and open at its upper end; a tubular member positioned above said plunger and movable axially thereof; a valve forming head closing the lower end of said tubular member and engageable with the end of said plunger for closing the same; means projecting from said head into said plunger; and means cooperating with said projecting means for limiting axial movement of said tubular member relatively to said plunger.

12. In a pumping mechanism of the class described, a stationary tubular plunger mounted in vertical position and open at its upper end; a

tubular member positioned above said plunger and movable axially thereof; a valve forming head closing the lower end of said tubular member and engageable with the end of said plunger for closing the same; means projecting from said head into said plunger; and means cooperating with said projecting means for limiting axial movement of said tubular member relatively to said plunger, said tubular member being

10 freely rotatable relatively to said plunger.

13. In a pump of the class described, a stationary tubular plunger; a tubular member; a head closing one end of said member, said member having lateral openings formed therein, said head being engageable with the end of said plunger for closing the same; engagement means carried by said head projecting beyond the end of said plunger; and means carried by said plunger engageable with said engagement means

15 for limiting axial movement of said tubular member relatively to said plunger in one direction.

20 CHALON E. BRIDWELL.
